UNITED STATES PATENT OFFICE.

GEORGE R. VAN SCHOICK, OF COLDWATER, MICHIGAN, ASSIGNOR OF ONE-HALF TO F. W. STEWART, OF SAME PLACE.

WRENCH.

SPECIFICATION forming part of Letters Patent No. 606,317, dated June 28, 1898.

Application filed November 30, 1897. Serial No. 660,244. (No model.)

To all whom it may concern:

Be it known that I, GEORGE R. VAN SCHOICK, a citizen of the United States, residing at Coldwater, in the county of Branch and State of Michigan, have invented a new and useful 5 Wrench, of which the following is a specification.

The invention relates to improvements in wrenches.

10 The object of the present invention is to improve the construction of nut-wrenches, and to provide a simple, strong, and durable one which will be inexpensive in construction and which will be capable of firmly gripping 15 a nut.

The invention consists in the construction and novel combination and arrangement of parts, as hereinafter fully described, illustrated in the accompanying drawings, and 20 pointed out in the claims hereto appended.

In the drawings, Figure 1 is a perspective view of a wrench constructed in accordance with this invention. Fig. 2 is a longitudinal sectional view of the same. Fig. 3 is a de- 25 tail perspective view of the dog.

Like numerals of reference designate corresponding parts in the several figures of the drawings.

1 designates a shank provided with a sta- 30 tionary jaw 2, and having a sliding jaw 3 mounted upon it and coöperating with the stationary jaw. The sliding jaw consists of a sheet-metal casing 4 and a metal block 5. The casing consists of parallel sides and a 35 connecting back piece, and the block 5 is interposed between the sides of the casing and is spaced from the back portion 6 to provide an opening or way for the shank 1. The sides of the casing and the block 5 are perforated 40 for the reception of rivets 7 or other suitable fastening devices for connecting the parts.

The shank 1 is provided at one side with a series of teeth 8, shouldered toward the sta- 45 tionary jaw 2, and adapted to be engaged by corresponding reversely-shouldered teeth 9 of a dog 10, which is housed within the cas- ing of the sliding jaw and which is connected with an operating-lever 11.

The dog 10 is substantially triangular in 50 side elevation, and is provided at its apex with a perforated ear 12, which is pivoted to

a corresponding ear 13 of the lever 11 by a pin 14 or other suitable pivot. The ear 13 of the lever 11 is located adjacent to one end thereof, and this end 15 is connected with the sliding 55 jaw by a link 16. The inner end of the link 16 is pivoted to the adjacent end of the operating-lever, and the outer end of the link is pivoted to the sliding jaw by a pin or rivet 17 at a point adjacent to the block 5, the lat- 60 ter being recessed, as shown, to receive the link. The recess 18 of the block 5 forms an inner face disposed at an angle to the shank and forming a stop for the link when the dog 65 is out of engagement with the shank.

When the dog engages the shank, its pivot 14 forms a fulcrum for the operating-lever 11, and the link and that portion of the lever be- 70 tween it and the pivot 14 form a toggle connection, whereby when the handle portion of the operating-lever is pressed toward the shank 1 the sliding jaw will be forced in the direction of the stationary jaw and will firmly grip a nut or other object to which the wrench is applied.

The link is normally forced in the direction of the shank to disengage the dog as soon as the handle of the operating-lever is released by a spring 19, disposed substantially parallel with the adjacent portion of the operating- 80 lever 11 when the dog is out of engagement and having one end fitting in a notch 20 of the outer edge of the link and its other end se- cured to the casing. The outer end of the spring is provided with an enlargement or 85 head 21, extended laterally from the spring and engaging notches 22 of the casing. Be- 90 tween its ends the spring bears against a stop 23, consisting of a rivet or other suitable device located adjacent to the head or enlarge- 95 ment.

When the toggle connection is swung out- 95 ward beyond the center, it forms a lock, and the operator is only required to exert a pres- 100 sure sufficient to overcome the power of the spring. As soon as the operating-lever is re- leased the spring throws the dog out of en- gagement with the shank.

The invention has the following advantages: The wrench is simple and comparatively inex- 100 pensive in construction, it possesses strength and durability, and is capable of firmly grip-

ping a nut or other object. The dog, link, and spring are housed within the casing, and the toggle connection operates to force the sliding jaw in the direction of the stationary one and serves as a lock.

Changes in the form, proportion, and minor details of construction may be resorted to without departing from the spirit or sacrificing any of the advantages of this invention.

10. What I claim is—

1. In a wrench, the combination of a shank provided with teeth, a stationary jaw mounted on the shank, a sliding jaw arranged on the latter and provided with an opening or way

15 to receive the same, a dog loosely arranged within the sliding jaw and provided with teeth for engaging the shank, an operating-lever pivoted between its ends to the dog, and a link pivoted to the lever and to the sliding

20 jaw and forming a toggle connection between the dog and the sliding jaw, substantially as and for the purpose described.

2. In a wrench, the combination of a shank provided with teeth, a stationary jaw mounted

25 on the shank, a sliding jaw arranged on the latter and provided with an opening or way to receive the same, a dog loosely arranged within the sliding jaw and provided with teeth for engaging the shank, an operating-lever

30 pivoted between its ends to the dog, a link pivoted to the lever and to the sliding jaw and forming a toggle connection between the dog and the sliding jaw, and a spring engag-

35 ing the toggle connection and adapted to break the same to throw the dog out of en-

gagement with the shank, substantially as described.

3. In a wrench, the combination of a shank provided with a stationary jaw, a sliding jaw mounted on the shank and having a casing 40 provided with notches, a dog arranged within the casing, a lever pivoted between its ends to the dog, a link connecting the lever and the sliding jaw and forming a toggle connection, said link being provided at its outer 45 edge with a notch, a spring engaging the notch of the link and provided with lugs fitting in the notches of the casing, and a stop forming a support for the spring between the ends of the same, substantially as described. 50

4. In a wrench, the combination of a shank provided with teeth, a stationary jaw, a sliding jaw composed of a casing and a block arranged between the sides of the casing and provided with a recess forming a face ar- 55 ranged at an angle to the shank and serving as a stop, a dog arranged within the sliding jaw, a lever pivoted between its ends to the dog, a link connecting the lever and the sliding jaw and arranged to engage the said face, 60 and a spring for holding the link normally in engagement with the face of the block, substantially as described.

In testimony that I claim the foregoing as my own I have hereto affixed my signature in 65 the presence of two witnesses.

GEORGE R. VAN SCHOICK.
